(57) **CLAIM**

The ornamental design for a cap holder for a container as shown and described.

DESCRIPTION

FIG. 1 is a top perspective view of a first embodiment of a cap holder for a container;

FIG. 2 is a bottom perspective view of the design of FIG. 1;

FIG. 3 is a front view of the design of FIG. 1;

FIG. 4 is a left side view of the design of FIG. 1, wherein the right side view is a mirror image thereof;

FIG. 5 is a top view of the design of FIG. 1;

FIG. 6 is a top perspective view of the design of FIG. 1, shown in an alternate position of use;

FIG. 7 is a partial cross-sectional view thereof, taken in the direction of line 7-7 on FIG. 6;

FIG. 8 is a top perspective view of a second embodiment of a cap holder for a container;

FIG. 9 is a bottom perspective view of the design of FIG. 8;

FIG. 10 is a front view of the design of FIG. 8;

FIG. 11 is a left side view of the design of FIG. 8, wherein the right side view is a mirror image thereof;

FIG. 12 is a top view of the design of FIG. 8;

FIG. 13 is a top perspective view of the design of FIG. 8, shown in an alternate position of use; and,

FIG. 14 is a partial cross-sectional view thereof, taken in the direction of line 8-8 on FIG. 13.

The evenly broken lines are shown for the purpose of illustrating both the boundaries of the claim as well as exemplary environmental subject matter. The dot-dash broken lines represent the designation of enlarged cross-sectional views. None of the broken lines form part of the claimed design.
